CLAIM

The ornamental design for a toe stop for an in-line skate, as shown and described.

DESCRIPTION

FIG. 1 is a side view of a toe stop for an in-line skate showing my new design, the broken line showing of the skate is for illustrative purposes only and forms no part of the claimed design;

FIG. 2 is a front elevational view thereof, the broken line showing of part of the skate is for illustrative purposes only and forms no part of the claimed design;

FIG. 3 is a perspective view thereof;

FIG. 4 is a right side elevational view thereof;

FIG. 5 is a left side elevational view thereof;

FIG. 6 is a front elevational view thereof;

FIG. 7 is a rear elevational view thereof;

FIG. 8 is a top plan view thereof; and,

FIG. 9 is a bottom plan view thereof.
